UNITED STATES PATENT OFFICE.

JAMES MEIKLEJOHN, OF LOCKPORT, NEW YORK.

SAFETY APPLIANCE FOR WEAVING-MACHINES.

1,316,914.

Specification of Letters Patent. Patented Sept. 23, 1919.

Application filed March 19, 1919. Serial No. 283,546.

To all whom it may concern:

Be it known that I, JAMES MEIKLEJOHN, a subject of the King of Great Britain, residing at Lockport, in the county of Niagara 5 and State of New York, have invented a new and useful Improvement in Safety Appliances for Weaving-Machines, of which the following is a specification.

This invention relates to means adapted 10 to be applied to weaving machines, particularly of the jacquard type, for preventing injury to parts of the machines.

In machines of the jacquard type in which the operation of the machines is controlled 15 by pattern cards, it sometimes happens that the card-carrying cylinders do not present the cards in proper relation to the needle-board, in which case the machine may become jammed, causing injury or breaking of 20 parts of the actuating mechanism and of the needle-board, needles and hooks, pattern cards, or the cylinder.

The objects of the invention are to provide a machine of this kind in which injury to the actuating mechanism of the 25 weaving machine is avoided in case the pattern card cylinder should fail to take the proper position relatively to the needle-board; also to provide means for preventing 30 injury to the needles, needle-board or patterns when the pattern card cylinder assumes an incorrect position; also to improve the construction and operation of machines of this kind in other respects hereinafter 35 specified.

In the accompanying drawings:

Figure 1 is a fragmentary elevation of a weaving machine provided with the means embodying the invention for preventing injury 40 to the machine.

Fig. 2 is a similar fragmentary view showing the pattern cylinder of the machine in an incorrect position and showing the parts of the machine in a position to 45 prevent injury to the machine.

Fig. 3 is a fragmentary top plan view, on an enlarged scale, of the cylinder and needle-board in an incorrect position, and showing the stop for preventing injury to the 50 needle-board, needles, hooks, and cylinder corners.

Fig. 4 is a fragmentary sectional elevation thereof on line 4—4, Fig. 3, showing the cylinder in correct position in regard to 55 the needle-board.

Fig. 5 shows in elevation a part of a weaving machine and means of modified construction for preventing injury to the machine.

Fig. 6 is a view similar to Fig. 5, showing the parts in different positions.

The drawings show the invention as applied to a jacquard weaving machine of well known construction, which includes a frame A on which the griffs B B' are slidably mounted to move vertically, the griffs being provided with the usual knives (not shown) adapted to coöperate with hooks b. C C' represents the usual cylinders or carriers by means of which the pattern cards 70 are brought into operative relation to the needle-boards D D'. The cylinders C include the usual perforated faces c with which the pattern cards are adapted to register, and are journaled at their opposite 75 ends in suitable frames c' which are movable to place the cylinders and the pattern cards which are held thereon into and out of operative relation to the needle-boards. Each of the frames c' is preferably provided 80 with the usual positioning member c² for the cylinder, which member is adapted to engage with corner posts or positioning stops c³ arranged at the ends of the cylinders to hold the cylinders in proper 85 positions to be presented to the needle-boards. The cylinders may be intermittently rotated by any suitable or desired means (not shown) to advance the pattern cards one at a time, and are moved toward and from 90 the needle-boards by means of slidably mounted rods E. These rods, in the construction shown in Figs. 1 and 2, are provided with arms or extensions e rigidly secured thereto and each rod has an inclined 95 slot in which a pin e', extending outwardly from one of the griffs B B', is adapted to engage. The vertical movements of the pins e' is transmitted through the rods E to the cylinders C and causes the cylinders C to 100 move into and out of operative relation to the needle-boards. All of these parts are of well known construction and of themselves constitute no part of this invention.

It will be seen that when a pattern card 105 carrier or cylinder is not placed into the correct position for moving into operative relation to the needle-board, for example, into a position such as shown in Figs. 2 and 3, the usual movement of the cylinder to- 110

ward the needle-board will not be possible without injury to some part of the machine. For this purpose it is desirable to provide means whereby injury to the machine will be avoided if the cylinder assumes an incorrect position with regard to the needle-board, and the following construction is preferably employed: Since the griffs are of sufficient weight to move to their lowest 10 positions by gravity, connecting links F F' are provided between the griffs and the usual actuating levers G G' which will permit the griffs to descend by gravity and permit the positively moving levers G G' to move to 15 the full limits of their paths of movement without forcing the griffs to the limits of their paths of movement. This is accomplished by providing a lost motion connection between each of the levers G G' and 20 the links F F', in which pins *g* of the levers G G' may move. Consequently, if the cylinder C should assume the position shown in Figs. 2 and 3, thus limiting the inward movement of the cylinder toward the needle-board, the parts will occupy the relative 25 position shown in Fig. 2, in which the pin *g* moves to the lower portion of the slot, thus permitting the positively actuated lever G to move throughout the full extent of its 30 movement and permitting the griffs B to move through only a part of its movement, thus avoiding injury to the actuating mechanism for the griffs or for the cylinder. The 35 fact that the griffs do not in such a case move through the full limits of their movement and that consequently for a short interval of time the machine will fail to operate in accordance with the pattern, is not sufficient to injure the work, since the fact 40 that a griff does not move to the full limit of its movement will immediately attract the attention of an operator so that the machine may be stopped without delay and the defect remedied. The lost motion connection 45 between the griff and the actuating lever prevents breaking or injury of the slotted member *e*, to the cylinder, needle-board, needles, hooks, or any other parts of the machine or of the actuating mechanism therefor.

In case the pattern card cylinder C is presented to the needle-board in any position other than its correct position, injury to the needles, hooks, needle-board, or cylinder corners is very likely to result, since an edge or corner of the cylinder may press against the needles *d* and bend or break the same. In order to prevent this from occurring, a stop or guard H is preferably provided at each end of the needle-board and is arranged to engage the corner posts or positioning stops *c*³ of the cylinder C in case the cylinder is presented edgewise to the needle-board, as shown in Figs. 2 and 3. 65 These stops, see particularly Figs. 3 and 4,

extend outwardly from the needle-board to a sufficient extent to prevent the cylinder from touching any of the needles in case the cylinder is not properly presented to the needle-board. In case the cylinder approaches the needle-board in proper relation thereto, the stops or guards H enter into recesses formed in the cylinders between the corner posts *c*³, as shown in Fig. 4, and do not in any way interfere with the operation 75 of the machine. If the stops H limit the movement of the pattern card cylinder toward the needle-board, no harm will be done to the cylinder actuating mechanism, owing to the lost motion connection herein-before described.

In case the pattern card cylinder is not actuated through the medium of the griffs, such as in a double-acting single cylinder machine, or in any jacquard machine in 85 which the cylinder is operated independently of the griff, a lost motion connection of different form may be provided. For example, in Figs. 5 and 6 the pattern card cylinder C is actuated by means of a rod I 90 slidably arranged in bearings *i* on the frame of the machine, reciprocatory motion being imparted to the rod I by means of a link *k* actuated by means of an oscillatory arm K secured on an oscillatory shaft *k*'. In 95 this case the lost motion is provided by making the arm K in two parts, the lower part *k*² being pivotally connected with the upper part *k*³, and a spring L preferably connects the two parts of the arm to hold 100 the same in their normal positions. If the pattern card cylinder C assumes an incorrect position in regard to the needle-board, the parts *k*² *k*³ of the lever move relatively 105 to each other as shown in Fig. 6, against the action of a spring L, thus permitting the positively driven part *k*² of the arm K to move through its usual path of movement without carrying the part *k*³ and parts connected therewith through their usual paths 110 of movement thereby preventing injury to the mechanism.

By means of the construction described, comparatively inexpensive changes in weaving machines as now constructed serve to 115 prevent accidents to the machines. The mechanism described therefore prevents the waste of time incurred by the breaking of parts of the weaving machines and does not in any way interfere with the proper operation 120 of the parts when the same are in correct positions. The lost motion connection not only acts in case the cylinder assumes an incorrect position relatively to the needle-board, but also if for any other cause the 125 proper operation of the machine is interfered with, for example in case the pattern cards become wound about a cylinder or if some foreign substance or object enters between the cylinder and the needle-board. 130

The lost motion connection is also an indicator as to the conditions of the bearings of the griffs and movable parts connected therewith, since if the bearings need lubrication to such an extent that the griffs will not drop by gravity, the lost motion connections will attract the operator's attention to this condition and the machine will not operate properly until the defect has 10 been remedied. This prevents the wearing out of the bearings due to lack of lubrication, which results if the griffs are positively driven.

I claim as my invention:

15 1. In a jacquard weaving machine, the combination of a needle-board, a pattern card carrier adapted to move into and out of operative relation to said needle-board, a projection on said needle-board adapted to 20 stop the movement on said carrier toward the needle-board when the carrier is in an incorrect position, means for actuating said carrier, and a lost motion connection in said actuating means which operates only when 25 the movement of said carrier relatively to said needle-board is resisted.

2. In a jacquard weaving machine, the combination of a pattern card carrier which is movable into and out of an operative 30 position, a griff, a connection between said griff and said carrier for actuating said carrier, a driving mechanism for said griff, and a lost motion connection in said driving mechanism which operates only when the 35 movement of the griff, of said carrier, or of said connection between said griff and said carrier is resisted.

3. In a jacquard weaving machine, the combination of a pattern card carrier which 40 is movable into and out of an operative position, a griff operatively connected to actuate said carrier, positively driven mechanism for imparting movement to said griff, and a lost motion connection between 45 said mechanism and said griff, said lost motion connection operating only when the

movement of said carrier into its operative position or of said griff is resisted.

4. In a jacquard weaving machine, the combination of a needle-board, a pattern 50 card carrier adapted to move into and out of operative relation to said needle-board, and a stop device on said needle-board adapted to coöperate with said carrier to limit the movement of said carrier toward 55 said needle-board when said carrier is in an incorrect position relatively to said needle-board.

5. In a jacquard weaving machine, the combination of a needle-board, a pattern 60 card carrier adapted to move into and out of operative relation to said needle-board, said carrier having a recessed portion, and a stop device on said needle-board adapted to enter said recessed portions when said 65 carrier is in the correct operative position with regard to said needle-board and to limit the movement of said carrier toward said needle-board when said carrier is in an incorrect position relatively to said 70 needle-board.

6. In a jacquard weaving machine, the combination of a needle-board, a pattern card carrier adapted to move into and out of operative relation to said needle-board 75 and having recessed portions at opposite ends thereof, and stops arranged at opposite ends of said needle-board and adapted to enter into said recessed portions when the carrier is in a correct operative position with regard to said needle-board and to limit the movement of said carrier toward 80 said needle-board when said carrier is in an incorrect position relatively to said needle-board.

Witness my hand, this 10th day of March, 1919.

JAMES MEIKLEJOHN.
